United States Patent Office

Des. 218,140
Patented July 28, 1970

218,140

IMPACT WRENCH

Kurt Gerhardt Johannsen, Flagstaff Hill, Adelaide,
South Australia, Australia, assignor to Undoolya
Pty. Limited, Adelaide, South Australia, Australia

Filed May 6, 1969, Ser. No. 17,030

Term of patent 14 years

Int. Cl. D8—02

U.S. Cl. D8—29

FIG. 1

FIG. 2

FIG.3

FIG. 4

FIG. 5

FIG. 6

FIG. 1 is a perspective view of the impact wrench of the invention;

FIG. 2 is a perspective view of the impact wrench, in collapsed, inoperative form;

FIG. 3 is a front elevation of the impact wrench as collapsed;

FIG. 4 is a side elevation of the impact wrench of FIG. 3;

FIG. 5 is a top plan of the impact wrench of FIG. 3; and

FIG. 6 is a bottom view of the impact wrench of FIG. 3. I claim:

The ornamental design for an impact wrench, as shown.
